RASMUS B. SORENSEN, OF TONOPAH, NEVADA, ASSIGNOR OF ONE-HALF TO MARTIN L. STROTHER, OF TONOPAH, NEVADA.

CAR REPLACER AND DERAILER.

1,074,754.

Specification of Letters Patent.

Patented Oct. 7, 1913.

Application filed September 18, 1912. Serial No. 721,022.

To all whom it may concern:

Be it known that I, RASMUS B. SORENSEN, a citizen of the United States, residing at Tonopah, in the county of Nye and State of Nevada, have invented a new and Improved Car Replacer and Derailer, of which the following is a specification.

My invention is an improved device having for its object to provide an effective, inexpensive means for causing cars to be derailed and replaced as may be desired.

In its general nature the invention includes a device for each rail, each device including a rail clamp for gripping the rail and a member hinged to the clamp to swing over the rail from one side to the other so as to be susceptible of location in a place out of the way when not in use, and capable of being swung into position when it is desired to employ the device to perform its operative functions. Each device also includes a bed plate having spiked members, or their equivalents, for engaging the rail ties when the device is in operative position to prevent displacement of the bed plate. The bed plate of one device is of wedge shape and is adapted to rest against the head of the rail to abut a wheel flange and direct the wheel off the rail; the bed plate of the other device carries a tread plate and a guide rail, the same being susceptible of horizontal adjustments to facilitate replacing the car.

More subordinately the invention includes novel details of construction, combination and arrangement of parts, all of which will first be fully described and then specifically pointed out in the appended claims, reference being had to the accompanying drawings, in which—

Figure 1 is a perspective view illustrating the invention in use with the parts in position to derail the car. Fig. 2 is a perspective view illustrating the invention with the parts in position to permit the passage of a train without derailing. Fig. 3 is an enlarged top plan view of one part of the invention. Fig. 4 is a cross section on the line 4—4 of Fig. 3. Fig. 5 is a top plan view of the other part of the invention. Fig. 6 is

a cross section on the line 6—6 of Fig. 5. Fig. 7 is a cross section on the line 7—7 of Fig. 5.

In the drawings in which like numerals and letters of reference designate like parts in all of the figures, 1 represents the bed plate of the inner member which is of wedge shape in top plan view and has its pointed end 2 adapted to lie in the direction of the car to be derailed, one side of the bed plate 1 lying in contact with the rail 13. The bed plate or replacing member 1 has an inclined front portion 3, and a transverse groove 4 on its underside to fit over and receive the clamping plate 10 of the clamp 9, as shown in Fig. 4. The clamp 9 is of the rail-base-engaging type and the plate 10 is secured by a suitable bolt and nut device 11.

6 is a horizontal strap that is secured at 7 to the bed plate 1 and is hinged at 8 to the clamp 9 so that the bed plate 1 may be located as shown in Fig. 1 of the drawings and in full lines in Figs. 2 and 3, or it may be swung over as indicated in dotted lines in Fig. 4 and by full lines in Fig. 2 to lie on the outside of the track and out of the way. The bed plate 1 is provided with spikes 12 on its underside to engage the rail ties and prevent displacement of the bed plate when it is in its operative position.

14 are the car wheels which are adapted to coöperate with the derailer and replacer as will be hereinafter made clear, and 15 designates a car to be derailed.

16 designates the bed plate or member of the other section of the invention and this plate has the front end beveled or inclined as at 17 with the extreme front edge further beveled as at 18 to aid in replacing the car on the rails. The bed plate 16 has a groove 19 on its underside to receive the clamp plate 20 of the rail clamp 22 which plate 20 is secured in place by a bolt and nut 21.

26 designates the tread plate to which the hinged member 24 is secured at 25. The hinged member 24 is hinged at 23 to the clamp 22 so that the tread plate 26 may be swung over the rail 13 and bed plate 16 as indicated in full lines in Figs. 1, 5 and 7

or it may be swung in clear of the rails as indicated in full lines in Fig. 2 and dotted lines in Fig. 7. The tread plate 26 has fingers or projections 27 that engage the sides 5 of the bed plate 16 and rail head as best indicated in Figs. 1, 5 and 7 of the drawings.

The outer end of the tread plate 26 is beveled off as at 28 to facilitate the wheel 14 riding up onto the same. The tread plate 10 26 is adjustably secured to the bed plate 16 by a bolt and nut device 29—30 that passes through the tread plate 26 and through a slot 31 in the bed plate 16 whereby the tread plate 26 may be turned on a pivot 25 in 15 a horizontal direction.

The inner or front end of the tread plate 26 is socketed at 32 to receive the projection 33 of the guide rail 34, which is also pivotally and adjustably secured at 35 to the bed 20 plate 16 in a manner similar to the connection 29—30. The front edge of the guide rail 34 is beveled at 36 to form a continuation, as it were, of the bevel 18 so as to facilitate the wheel 14 riding up onto the 25 guide rail 35 with the tread of the wheel in engagement with the guide rail and the flange of the wheel in contact with the side of the guide rail between it and the track rail.

30 In operation when it is desired to derail the car, the parts are adjusted as indicated in Fig. 1, so that as the car is moved forwardly in Fig. 1 the flange of one wheel 14 will engage the bed plate 1 while the other 35 wheel 14 will ride up onto the tread plate 26 clear of the rail head; consequently the trucks of the car will be directed off of the rails onto the ties as they pass over the parts 1 and 16.

40 In order to replace the car on the track the wheel are run up onto the parts 3 and 16, it being understood that the guide rail 34 and tread plate 26 are so adjusted laterally as to come into the proper position with 45 respect to the wheel that is to ride up the same. The wheels riding up the members 1 and 16 will be directed into proper position with relation to the track rails so as to restore the truck and the car back onto the 50 track rails in a manner which will be well understood by those skilled in the art.

From the foregoing description taken in connection with the accompanying drawings it is believed that the complete construction and advantages of the invention 55 will be apparent to those skilled in the art, and I desire it to be understood that slight changes in the details of construction, design and proportional parts may be made 60 without departing from the invention and the scope of the appended claims.

What I claim is:

1. In a derailer and replacer, a clamp securable to the rail, a member hinged to said

clamp on an axis parallel to the rail and 65 adapted to be bodily swung over the rail into operative position, and means including rail-tie-engaging members for holding said hinged member from slipping.

2. In a derailer and replacer, a rail engaging clamp, a replacing member, a hinged connection between said member and said clamp, said replacing member being adapted to be bodily swung over the rail into operative position, said member having a bottom slot 70 to receive a part of said clamp and having a top recess to receive said hinged connection.

3. In a derailer and replacer, a rail engaging clamp, a replacing member, a hinged 80 connection between said member and said clamp, said replacing member being adapted to be bodily swung over the rail into operative position, said member having a bottom slot to receive a part of said clamp and 85 having a top recess to receive said hinged connection, and tie engaging spikes on the underside of said replacing member.

4. In a derailer and replacer, a rail clamp, a bed member designed to rest on the ties 90 close to the rail, a tread plate hinged to said clamp on an axis paralleling the rail and bodily swingable over the rail and bed member to lie on the same, and means for securing said tread plate to said bed member. 95

5. In a derailer and replacer, a rail clamp, a bed member designed to rest on the ties close to the rail, a tread plate hinged to said clamp on an axis paralleling the rail and bodily swingable over the rail and bed member to lie on the same, means for securing said tread plate to said bed member, and a 100 guide rail mounted on said bed member and co-operating with said tread plate.

6. In a derailer and replacer, a rail clamp, 105 a bed member designed to rest on the ties close to the rail, a tread plate hinged to said clamp and swingable over the rail and bed member to lie on the same, means for securing said tread plate to said bed member, a 110 guide rail mounted on said bed member and co-operating with said tread plate when in operation, and said tread plate and said guide rail having inter-projecting portions to form a movable joint between them. 115

7. In a derailer and replacer, a rail clamp, a bed member designed to rest on the ties close to the rail, a tread plate hinged to said clamp and swingable over the rail and bed member to lie on the same and a bolt 120 and socket connection between said bed member and said tread plate to secure said tread plate to said bed member with provisions for horizontal adjustment.

8. In a derailer and replacer, a rail clamp, 125 a bed member designed to rest on the ties close to the rail, a tread plate hinged to said clamp and swingable over the rail and

bed member to lie on the same and a bolt and socket connection between said bed member and said tread plate to secure said tread plate to said bed member with provisions for horizontal adjustment, and a guide rail mounted on said bed member and inter-engaging said tread plate, and a bolt and

slot connection between said bed member and said guide rail with provisions for horizontal adjustment.
